CHARLES STOLL, OF BROOKLYN, NEW YORK, ASSIGNOR TO CENTRAL FURNITURE
FRAME CO. INC., OF BROOKLYN, NEW YORK, A CORPORATION

DESIGN FOR A SETTEE OR SIMILAR ARTICLE

Application filed June 15, 1929. Serial No. 31,717. Term of patent 3½ years.

To all whom it may concern:

Be it known that I, CHARLES STOLL, a citizen of the United States, residing at Brooklyn, in the county of Kings and State of New York, have invented a new, original, and ornamental Design for Settee or Similar Article, of which the following is a specification, reference being had to the accompanying drawing, forming part thereof.

The figure is a perspective view of a settee or similar article, showing my new design. The ornamentation shown is continued throughout the portion shown plain on the drawing.

I claim:

The ornamental design for a settee or similar article, as shown and described.

CHARLES STOLL.
